UNITED STATES PATENT OFFICE.

CHARLES HAESELER, OF PHILADELPHIA, PENNSYLVANIA.

PERCUSSIVE TOOL.

1,093,048.

Specification of Letters Patent. Patented Apr. 14, 1914.

Application filed November 6, 1913. Serial No. 799,417.

To all whom it may concern:

Be it known that I, CHARLES H. HAESELER, a citizen of the United States, residing in the city of Philadelphia, county of Philadelphia, and State of Pennsylvania, have invented certain Improvements in Percussive Tools, of which the following is a specification.

My invention relates to means for turning the bits of percussive tools, particularly hammer drills, and it is characterized by the combination with a cylinder, of a percussive piston provided with a tapered section, a revoluble chuck, and means comprising a lever actuated by said tapered section and a clutching member actuated by said lever to effect a turning movement of the chuck, the preferred construction comprising a lever acting transversely to the piston and to which the power is applied between the fulcrum and the work.

The primary purpose of my invention is to effect a positive and substantial turning movement of the drill bit by simple and compact means actuated by a section of a revoluble piston slightly tapered, so as to avoid objectionable weakness and produce the maximum turning movement of the bit with the minimum reduction in the normal diameter of the piston or hammer.

In the accompanying drawings, Figure 1 is a vertical sectional view of a drill embodying my improvements; Fig. 2 is a sectional view taken on the line 2—2 of Fig. 1; Fig. 3 is a sectional view taken on the line 3—3 of Fig. 1; Fig. 4 is a part sectional elevation at right angles to the view shown in Fig. 1; Fig. 5 is a broken sectional view illustrating modifications in the construction, and Fig. 6 is an elevation of a detached piston having a reverse taper.

The drill, as shown in the drawings, comprises the cylinder 1 containing a piston 2, a chuck 3 having a sleeve 4 revoluble on the reduced forward end 5 of the cylinder, a bit 6 movable longitudinally in and adapted to be turned by the chuck, a housing 7 provided with a sleeve 8 telescoped on the sleeve 4 and a bearing 9 engaging the bearing flange 10 on the sleeve 4, and the tie rods 11 which are engaged to lugs 12 on the head of the cylinder, pass between lugs 13 in the housing and are provided with nuts 14 thereon for supporting coiled springs 15 which support the housing. Within the housing 7, on the top of the sleeve 4, above

the flange 10, is fixed a ratchet ring 16 having the peripheral teeth 17, and surrounding this ring is a collar 18 provided with the pawls 19 staggered in relation to the ratchet teeth and normally held in position for engagement therewith by the springs 20 on the collar, the latter bearing and turning on the cylinder section 5 and bearing flange 10. Bent levers 21 are respectively fulcrumed at one end on the bearings 22 within the housing 7 and are pivotally connected at their opposite ends with links 23 which are pivotally connected to the collar 18, the latter being provided with the peripheral channel 24 and the recesses 25 for the respective levers and links. Bearings 26, of hardened steel, are carried by the respective levers, between their ends, and extend inwardly therefrom into the apertures 27 through the collar. Balls 28, of hardened steel, are disposed in apertures 29 in the part 5 of the cylinder, being adapted to extend into the apertures 27 and through the wall of the cylinder.

The piston 1 is provided with the conical section 30 and the reduced cylindrical section 31 having substantially the diameter of the smaller end of the tapered section adjacent thereto, these sections engaging the balls 28 in different positions of the reciprocating piston, the balls being held in engagement with the piston by the actions of the springs 32 fixed within the housing 7 and bearing against the toggles formed by the levers 21 and links 23.

The piston 2 is reciprocated by the pressure of fluid introduced to the cylinder 1 from the duct 33 through the passages 34 and 35, alternately, under control of a valve 36, the fluid exhausting through the ports 36 and 37, in a known manner. The hammer or forward end 2' of the advancing piston delivers its blow to the block 38 movable in the forward end 5 of the cylinder, the block transmitting the blow to the bit 6.

During the movement of the piston from its rear to its forward position, the springs 32 act upon the levers 21 so as to move them and the balls 28 to their inner position, the levers acting through the links 23 to turn the collar 18 so as to retract the pawls 19. In the reverse movement of the piston 2, no turning movement is transmitted to the bit 6 while the cylindrical piston section 31 is in engagement with the balls 28, but on the

engagement of the tapered section 30 with such balls, the latter are moved outwardly against the bearings 26, the levers 21 are moved outwardly, the links 23 are caused to turn the collar 18 forward and the engaging pawl 19 acts through the ratchet mechanism 16 to turn the chuck 3 and the bit 6, the staggered relation of the pawls with reference to the ratchet teeth insuring a clutching engagement substantially at the beginning of the forward movement of the collar and the substantially tangential relation of the forwardly moving pawls to the ratchet ring providing for the most effective application of their thrust. As the movement of the lever ends connected with the links or the place of application to the work, is substantially twice that of their bearings 26, or the place of application of power, the diametral reductions in forming the conical section 30 and the cylindrical section 31 are comparatively small. It will be understood that the bearing of the collar 18 on the cylinder section 5 prevents irregular action by keeping the reciprocating parts in correct relation.

The construction may be modified as illustrated in Fig. 5, in which the sleeve 4 has the radial ratchet teeth 17' on the flange 10' revoluble on the bearing 9, and the collar 18' (turned on the cylinder section 5 by the action of the piston section 30 through the balls 28 on the levers 21) carries a ring 38' having the radial ratchet teeth 38'' which ride over the ratchet teeth 17' when moved reversely and positively engage when moved forwardly whereby the chuck sleeve 4 is turned. The collar 18' is provided with the ways 18'' and the ring 38' is provided with the lugs 38''' engaged and movable vertically in the ways, while a circular channel 39 in the collar contains a coiled spring 40 which bears upon the ring 38' to hold its teeth 38'' in engagement with the teeth 17'.

45 A piston 6' may be substituted for the piston 6, as illustrated in Fig. 6, in which the taper 30' is reverse to the taper 30, so that the turning operation will be effected in the downward movement of the piston, as may be desirable, particularly in operating through soft or plastic substances.

Having described my invention, I claim:

1. A percussive tool comprising a cylinder, a chuck connected in revoluble relation thereto, a piston having an inclined surface in said cylinder, and means whereby said inclined surface turns said chuck, said means comprising a lever having a fulcrum connection, a work connection and a connection with said inclined surface between said fulcrum and work connections.

2. A percussive tool comprising a cylinder, a chuck connected in revoluble relation thereto, a piston having a tapered sec-

tion movable in said cylinder, a collar adapted to turn on said cylinder, a lever having a fulcrum and a connection with said collar, means whereby said tapered section applies power to said lever between said fulcrum and connection, and clutching mechanism whereby said collar turns said chuck.

3. A percussive tool comprising a piston having an inclined surface, a cylinder in which said piston is reciprocated, a chuck connected in revoluble relation with said cylinder, clutching mechanism comprising an oscillating member for turning said chuck, and means operated by said inclined surface for moving said oscillating member, said means comprising a fulcrumed lever adapted to oscillate transversely to said piston, a device connecting said lever with said oscillating member and a device connecting said inclined surface with said lever between its fulcrum and its place of connection with said device first named.

4. A percussive tool comprising a piston having a tapered section, a cylinder in which said piston reciprocates, a collar adapted to turn on said cylinder, a lever, a bearing on which said lever is fulcrumed, a link connecting said lever and collar, and means whereby said tapered section applies power to said lever.

5. A percussive tool comprising a piston having an inclined surface, a cylinder in which said piston reciprocates, a collar adapted to turn on said cylinder, a chuck connected in revoluble relation to said cylinder, clutching mechanism whereby said collar turns said chuck, a lever fulcrumed so as to oscillate transversely to said piston, means whereby said lever turns said collar, and means whereby said surface moves said lever.

6. A percussive tool comprising a piston provided with a conical section and a cylindrical section having substantially the diameter of the smaller end of said conical section, a cylinder in which said sections reciprocate, said cylinder having an aperture therein, a ball disposed in said aperture and adapted for engagement with said sections, a lever adapted to be moved by said ball through the action of said conical section, means comprising a clutching device connected in oscillatable relation to said cylinder, a link connecting said lever and means, and a chuck having a clutching device adapted to be turned intermittently by the oscillation of said clutching device first named.

7. A percussive tool comprising a piston provided with an inclined surface, a cylinder in which said surface is reciprocated, said cylinder having an aperture therein, a device disposed in said aperture, a lever adapted to be moved transversely to said piston by said device, means adapted to be

turned relatively to said cylinder by said lever, said means having a movement of oscillation transverse to said cylinder, and a chuck connected in revoluble relation to said cylinder, said chuck having peripheral ratchet teeth adapted to be engaged by said means and lying within the path of movement thereof.

8. A percussive tool comprising a hammer having an inclined surface, a cylinder in which said hammer reciprocates, a chuck connected in revoluble relation to said cylinder, a ratchet ring connected with said chuck, a collar adapted to turn on said cylinder, pawls carried by said collar exterior to said ring, springs carried by said collar for holding said pawls in engagement with said ring, levers, bearings on which said levers are fulcrumed, links connecting said levers with said collar, springs for pressing

said levers toward said piston, and balls movable by said inclined surface whereby said levers are moved outwardly.

9. A percussive tool comprising a piston having an inclined surface, a cylinder in which said piston reciprocates, reciprocating means comprising a lever actuated by said inclined surface, a collar adapted to be oscillated on said cylinder by said means, one or more pawls carried by said collar, and a chuck having clutching means engaged by said pawl or pawls.

In testimony whereof I have hereunto set my name this fourth day of November, 1913, in the presence of the subscribing witnesses.

CHARLES H. HAESELER.
